UNITED STATES PATENT OFFICE.

WORCESTER HADDOCK, OF CINCINNATI, OHIO, ASSIGNOR OF ONE-HALF TO
EDWARD F. ABBOTT, OF COVINGTON, KENTUCKY.

CAR-BRAKE.

SPECIFICATION forming part of Letters Patent No. 241,538, dated May 17, 1881.

Application filed September 30, 1880. (No model.)

To all whom it may concern:

Be it known that I, WORCESTER HADDOCK, of Cincinnati, in Hamilton county, and State of Ohio, have invented certain new and useful 5 Improvements in Street-Car Brakes, of which the following is a specification.

A great many accidents occur from the breaking of some part of the brake when the car is going down an incline, and the object of my 10 invention is to prevent such accident; and my invention consists in such a construction, hereinafter described, as to accomplish this object.

In the accompanying drawings, Figure 1 represents a central longitudinal section through 15 a car. Fig. 2 represents the drum or shaft around which the brake-chains wind. Fig. 3 represents a vertical central section through Fig. 2. Fig. 4 is a plan view, showing the arrangement of the brake rods and levers.

20 A is the drum, which is attached to a rod or shaft, A', to which latter is attached a hand wheel or crank to be operated by the brakeman. A rod or pin, I, is screwed entirely through the upper end of this drum, and nuts a' are screwed 25 onto either end of said pin I. This pin is screwed through the drum, so that should one end of the pin be broken off the pin cannot slip through the drum.

B is the main brake-chain, one end of which 30 is connected to one end of the pin I, and between the drum and the nut a', and the other end of said chain is connected to the brake-rod E, which, in turn, is connected to one end of the usual brake-lever, E'. The latter is ful- 35 crumed to the car by the bolt e, provided with a suitable head to prevent the lever E' from falling to the ground.

C is an auxiliary or safety chain, one end of which is connected to the end of the pin I, op- 40 posite the end to which the chain B is attached, and this end of the said safety-chain C is between the drum and nut a'. The other end of the chain C is connected to the auxiliary brake-rod D, which latter is attached to the end of the 45 brake-lever E', and near the point where the rod E is connected to said brake-lever. The chain C is prevented from dragging on the ground by the spiral spring H, which is attached to the under side of the car. The 50 spiral spring is preferable to any other form of support, as it will permit the chain C to be

drawn forward as it is wound around the drum A without breaking it, (the spring,) and will immediately draw the chain C again up toward the bottom of the car, and prevent this chain 55 from dragging when the latter is unwound from the brake.

The brake-shoes F are attached to the rod F', which is connected to the brake-lever E' by the rod F², in the usual manner. 60

The manner in which my invention operates and its principal points of advantage are as follows:

The brake operates, in the usual manner, through the chain B and rod E, unless one of 65 these should break, in which event my invention will come into play. Suppose the car to be going down an incline and the chain B or rod E to break, the chain C will wind around the drum A, and, through the medium of the 70 rod D, will operate on the brake-lever E' in the manner as did the chain B and rod E. Thus no accident can occur from the breaking of the main brake chain or rod.

The manner in which the ends of the chains 75 are attached to the drum A is a great improvement over the ordinary method, and forms one feature of my invention. Ordinarily the brake-chain is attached to the drum by means of an eye projecting from the drum, and this eye is 80 very liable to be broken off. Instead of eyes I use a pin, I, as mentioned, which is screwed entirely through the drum, and projects a short distance from either side of the drum, as shown in Fig. 3. The chains B and C are attached 85 one to either end of this pin I, and held in position against the drum by the nuts a', screwed onto the ends of said pin, as shown in Fig. 2. By this construction it will be seen that the chains are held closely against the drum, and the ends of the pins I are therefore not so liable to break as eyes would be, for in the latter case the chains are connected to the eyes at a greater distance from the drum than in the case of the employment of the eyes, as shown; 95 but should one end of the pin I be broken off it will not affect the other end, as the pin, being screwed through the drum, cannot be pulled through.

What I claim as new, and desire to secure 100 by Letters Patent, is—

1. In a car-brake, the combination of the

main brake-chain B, rod E, and the auxiliary chain C and rod D, substantially as and for the purposes specified.

2. The combination of the brake-lever E', rods E and D, chains B and C, and the drum A, the latter being connected with the brake wheel or crank, substantially as and for the purposes specified.

3. The drum A, provided with the pin I, 10 screwed entirely through said drum, in combination with the chains B and C, the latter being held on said pin by the nuts a', substantially as and for the purposes specified.

4. The drum A, provided with the pin I, 15 screwed entirely through the said drum, in combination with the chains B and C, the latter being held on said pin by the nuts a', brake-shoes and brake-lever E', and connecting and operating mechanism, substantially as and for 20 the purposes set forth.

5. The combination of the drum A, connected with the brake wheel or crank, and provided with pin I, screwed through said drum, the

chains B and C, rods E and D, and the brake-lever E', substantially as and for the purposes 25 specified.

6. The combination of the drum A, connected with the brake wheel or crank and provided with pin I, screwed through said drum, the chains B and C, rods E and D, brake-lever 30 E', brake-shoes, car-frame, and wheels, and connecting and operating mechanism, substantially as and for the purposes set forth.

7. The combination of the vertical drum A and the two brake-chains B C, the latter connected to the drum, on opposite sides thereof and in the same horizontal plane, substantially 35 as and for the purposes specified.

8. The combination of the main brake-chain B, rod E, and the auxiliary chain C and rod 40 D, and a winding mechanism, for the purposes set forth.

WORCESTER HADDOCK.
